(57) **CLAIM**

The ornamental design for a facial slimming strap with earphones, as shown and described.

DESCRIPTION

FIG. 1 is a perspective view of a facial slimming strap with earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the facial slimming strap with earphones shown in an open state; and,

FIG. 10 is another perspective view of the facial slimming strap with earphones shown in the open state.

The broken lines in the drawings depict portions of the facial slimming strap with earphones that form no part of the claimed design.
